Primary Examiner — Susan Bennett Hattan*Assistant Examiner* — Lauren D McVey(74) *Attorney, Agent, or Firm* — DASCENZO Intellectual Property Law, P.C.(57) **CLAIM**

The ornamental design for a tattoo needle tube, as shown and described.

DESCRIPTION

FIG. 1 is a top, front isometric view of a tattoo needle tube showing our new design;

FIG. 2 is a front elevation view of the design of FIG. 1; FIG. 3 is a rear elevation view of the design of FIG. 1; FIG. 4 is a left side elevation view of the design of FIG. 1; FIG. 5 is a right side elevation view of the design of FIG. 1; FIG. 6 is a top plan view of the design of FIG. 1; FIG. 7 is a bottom plan view of the design of FIG. 1; and, FIG. 8 is a bottom, rear isometric view of the design of FIG. 1.

The broken lines immediately adjacent to the shaded areas depict the bounds of the claimed design, while all other broken lines are directed to environment. The broken lines form no part of the claimed design.

1 Claim, 5 Drawing Sheets(56)
